CLAIM

We claim the ornamental design for a display screen or portion thereof with icon, as shown and described.

DESCRIPTION

FIG. 1 is a front view of a display screen or portion thereof with icon showing our new design; and,

FIG. 2 is an enlarged front view of the icon thereof. The dash-dash broken lines depict a display screen or portion thereof that forms no part of the claimed design. The dot-dash broken lines in the figures illustrate a boundary of the claimed design and form no part thereof.
